TELEVISION

Manfred von Ardenne, Berlin, Germany, assignor
to Radioaktiengesellschaft D. S. Loewe, Berlin-
Steglitz, Germany, a company of Germany

Application April 27, 1932, Serial No. 607,720
In Germany April 29, 1931

2 Claims. (Cl. 178—6)

In the case of the television methods heretofore known the image is scanned as evenly as possible line by line in the one direction, and in equally even fashion in the direction at right angles thereto. For the recording of each picture element of equal size there is, therefore, from a practical standpoint, always the same amount of time available.

According now to a new method the velocity of scanning is varied, viz., dependent on certain properties of the picture element to be transmitted, and preferably the light intensity thereof. It is, for example, possible when scanning an image line by line to regulate the rate of scanning by the intensity.

An arrangement of this nature is illustrated in Fig. 1, while Figs. 2, 3 and 4 illustrate further modifications described in detail hereafter. In Fig. 1, 1 is a film, which it is assumed is advanced line by line in a direction vertical to the plane of the drawing. On this film there is reproduced through the medium of a lens 2 the fluorescent spot moving on the screen 3 of a cathode ray tube 4. This tube possesses a cathode 5, a Wehnelt cylinder 6, an anode 7 and a pair of deflecting plates 8. Behind the film 1 there may be provided a mat screen 9, so that the ray of light passing diffusely through the same controls a photo-cell 10. The photo-cell current is amplified by an amplifier 11, and controls the valve 12, through the medium of which the condenser 13 situated in parallel with the pair of deflecting plates 8 is charged by the potential source 14. In parallel with the condenser 13 there is a glow lamp 15, through the medium of which, when its ignition potential has been reached, the condenser 13 is discharged, whereby the scanning of the line commences afresh. In this manner the same image appears on the screen 3 of the valve 4 which was scanned on the film 1, either as positive or negative dependent on the polarity.

It is now of considerable importance to employ a modulation resistance, or a modulation resistance in a circuit, in which the resistance of the modulated element is independent of the conditions of the circuit to be modulated. The circuit described above possesses, for example, the disadvantage that for the purpose of maintaining the characteristic of the charging tube 12 the alternating charging potential requires to be increased artificially. According now to the invention, the condenser 13, in order to avoid this, is charged through the medium of the relatively constant internal resistance of a tilting apparatus 55 supplying a saw-tooth potential, whereby the

charging operation is retarded by a photo-modulated multiple electrode valve situated in parallel with the condenser 13. By employing a parallel tube of this nature the maximum potential occurring in the system is equal to the deflecting potential at the edge of the line. An arrangement of this nature is illustrated in Fig. 2. Although in this case the resistance of the modulating element depends on the conditions of the circuit to be modulated, the influence exerted is nevertheless a much smaller one. In this case it is of particular advantage to employ valves having a small reciprocal of the amplification factor, for instance screening grid valves. Although in this case there is also the possibility of compensating the potential variation, an approximate solution (valve with small reciprocal of the amplification factor) is nevertheless more simple and therefore to be preferred. As more clearly set forth in the following, a modulation of this nature is preferably obtained by intensity-modulated Braun tubes, in which the pairs of plates to be employed as the modulated resistance result in a resistance, which from a practical standpoint, is independent of the conditions of the circuit to be modulated.

In Fig. 2 similar elements are furnished with like reference characters to Fig. 1. In this case the condenser 13 is charged by the battery 14 through the medium of a saturated diode 16 especially with ionic discharge. It is necessary to employ a saturated ionic valve in order to obtain a linear charging curve of the condenser. The charging of the condenser is retarded by the parallel tube 17 controlled by the amplifier 11.

In the case of television apparatus such as described up to now it is necessary to link the image deflection with the line deflection by means of a line counting mechanism. The device hitherto employed for this purpose is of a relatively complicated kind. It has been found that it is sufficient to allow two generators for the line and image frequency, which are independent in themselves, to be acted upon by the same line modulator. Care merely requires to be taken that the image potential is modulated to a smaller degree than the line potential.

A modulation of image and line similar to this is performed in the case of the arrangement according to Fig. 3. This figure corresponds with Fig. 2, whereby, however, there is added the control of the image potential. This is effected by means of the tilting apparatus 18, which in similar fashion to that for the line potential, may consist of a potential source, a saturated diode, a charging condenser and a glow discharge space.

The saw-tooth tilting potential of this tilting apparatus is located at the image-deflecting plates 19. Intermediate line-by-line actuation of the film 1 is now omitted. In place of this the film is advanced image by image. The image potential is modulated by the tube 20 located in parallel with the charging condenser. As already stated above, the valves 17 and 20 are preferably constructed in the form of screening grid valves, in order to reduce the influence of fluctuating anode potential to a minimum.

This, however, is to be accomplished with the greatest advantage if the line and image potentials are modulated by a Braun tube. The method of carrying this into practice is illustrated in Fig. 4. In this case 21 and 22 are line or image tilting apparatus, the potentials of which are applied to the deflecting plates of the Braun transmission or receiving tube. The increase in potential is modulated by an additional Braun tube 24, the deflecting plates of which are parallel to those of the first Braun tube. The modulation occurs by reason of the intensity controlled flow of electrons between the pairs of deflecting plates 25 and 26, for instance by variation of the potential of the Wehnelt cylinder 27 of this tube. For the purpose of obtaining an effective modulation the pairs of deflecting plates 25 and 26 are set so close together that the fluctuating flow of electrons through the pairs of plates provides the modulation of the image and line potentials. The degree of modulation is adjusted by suitable internal resistances of the image and line tilting apparatus. The use of the Braun tube as conductivity modulator has the appreciable advantage that the conductivities between its pairs of plates are, from a practical standpoint, wholly independent of the conditions of the circuit to be controlled.

I claim:

1. In a television transmission device comprising a Braun tube having cathode, anode, deflecting means and a fluorescent screen, means for developing a cathode ray, a generator for produc-

ing deflecting voltages of saw tooth wave form connected to said deflecting means, a photo cell, a modulator resistance connected to said photo-cell and in parallel to said generator, said resistance serving for modulating said deflecting voltages proportional to the photo cell voltages varying with the light falling upon said photo cell, said resistance being approximately independent of the working conditions of said deflecting voltage generator and said deflecting means, 10 said resistance being constituted by the shunt resistance of two plates of a second Braun tube, comprising cathode, anode, two condenser plates and light intensity control means connected to said photo cell, the varying value of said resistance being determined by the strength of the cathode ray passing through said plates of said second Braun tube.

2. In a television transmission device comprising a Braun tube having cathode, anode, deflecting means and a fluorescent screen, means for developing a cathode ray, two generators for producing deflecting voltages of saw tooth wave form, one for line deflection and the other one for image deflection, connected to said deflecting means, a photo cell, two modulator resistances, each connected to said photo cell and in parallel to each of said generators, said resistances serving for modulating each said deflecting voltages proportional to the photo cell voltages varying with the light falling upon said photo cell, said resistances being approximately independent of the working conditions of said deflecting voltage generators and said deflecting means, said resistances being constituted by the shunt resistances of two pairs of plates of a second Braun tube, comprising cathode, anode, two pairs of condenser plates and light intensity control means connected to said photo cell, the varying value of said resistance being determined by the strength of the cathode ray passing through said plates of said second Braun tube.

MANFRED VON ARDENNE.
